UNITED STATES PATENT OFFICE.

WILLIAM B. GRIFFITH, OF PHILADELPHIA, PENNSYLVANIA, ASSIGNOR TO CHRISTENSEN & COMPANY, INC., OF BOSTON, MASSACHUSETTS, A CORPORATION OF MASSACHUSETTS.

STREET-MUSIC RACK.

Application filed December 14, 1922. Serial No. 606,771.

To all whom it may concern:

Be it known that I, WILLIAM B. GRIFFITH, a citizen of the United States, residing at West Philadelphia, in the county of Philadelphia and State of Pennsylvania, have invented a new and useful Improvement in Street-Music Racks, of which the following is a specification, reference being had thereto in the accompanying drawings.

19 This invention relates to a music rack for street use in connection with such musical instruments as the flute, piccolo and fife.

The main object of the invention is the provision of a music rack of the foregoing character which is simple in construction and convenient in use.

Another object of the invention is the provision of a rack which is capable of adjustment to suit the particular range of vision 20 of the user.

A further object is to secure a rack which when not in use may be folded up or collapsed into a small compass to permit it to be carried in the pocket of the user.

25 Other objects of the invention will be more specifically set forth and described hereinafter.

In its preferred embodiment my invention contemplates a music rack adapted to 30 be held between the arm pit and the forearm of the user when the forearm is in its usual raised position for manipulating the flute or other instrument. The rack may be made in one piece but is preferably made 35 in two parts relatively adjustable to each other to permit of folding in a small compass. One of said parts is formed to fit the arm pit of the user and the other part is shaped to engage the inner side and to 40 extend forwardly over the top of the forearm so that the rack may be firmly in position between the arm pit and the forearm of the user when walking or marching; the adjustable feature permitting the rack to be 45 adapted to persons of different size. Upon the forward part may be adjustably mounted a lyre of ordinary and usual construction for holding the sheets of music.

In the drawings, Figure 1 is a view in 50 perspective illustrating the method of using the preferred form of my music rack in which a musician is shown in dotted outline in playing position with a rack constructed in accordance with my invention shown in full lines in operative position;

Fig. 2 is a side elevation of the rack ready for use; Fig. 3 is a side elevation of the same folded up for insertion in a pocket; Fig. 4 is a detailed view on an enlarged scale of the adjustable connection of the two parts of the rack; and Fig. 5 is a similar view also on an enlarged scale of the lyre standard and mounting.

Referring to the drawings illustrating one form of my invention, there is shown a rack made in two parts, one of said parts having a curved portion 10 adapted to fit the arm pit and front of the shoulder of the user and a reversed straight portion 12 and the other of said parts being substantially right-angled with straight portions 14 and 16 connected by a curved portion 18. These two parts may be adjustably connected by any suitable means, one of which is shown consisting of a split collar 20 adapted to 55 encircle the portion 12 and having wings 22 bored to receive a headed screw 24. A butterfly nut 26 mounted on the screw may be used to draw the wings 22 together and thereby cause the collar 20 to grip the portion 12 tightly in any adjusted position. The collar may be provided with a bored extension 28 to receive the arm 14 of the second part or the collar 20 may be integral 60 therewith.

Any suitable music holding means may be mounted on the arm 16 of the second part such as a lyre of well known construction having a harp-shaped back 30 and a front fork 32 pivotally mounted and held 65 against the back by a spring 34. A finger piece 36 is carried by the fork 32 to facilitate its operation to permit the insertion of sheets of music between the back and fork. The lyre is mounted upon a standard 38 having its lower end provided with a flange 40 and a threaded portion 42 adapted to be 70 inserted in the bored wings 44 of a collar 46 mounted on the arm 16. A butterfly nut 48 may be used for drawing the wings 44 together to cause the collar to grip tightly 75 the arm 16.

In use, my rack is adjusted as shown in Figure 1 with the curved portion 10 mounted in engagement with the arm pit and 80 front of the shoulder and the second part arranged over the forearm near the elbow, the portion 14 being in engagement with the inner side of the forearm and the curved portion 18 in engagement with the top of 85 the arm 16.

the forearm and portion 16 projecting thereover and in front of the user. The rack should be so adjusted that it is held tightly in position between the forearm and the arm pit when the arm upon which it is mounted is in a raised position as shown in Fig. 1. This requires that the second part be adjusted upon the straight portion 12 of the first part, which adjustment is accomplished by loosening the butterfly nut 26, moving the second part into proper position upon the straight portion 12 and then securing it in that location by tightening the nut 26. At the same time the lyre should be adjusted upon the portion 16 of the second part according to the range of vision of the user, the adjustment in this case being similar to the former adjustment by manipulation of the butterfly nut 48.

20 When the rack is not in use, it may be reduced into a compass sufficiently small to permit its insertion in a pocket of the user by merely loosening the nuts 26 and 48, sliding the second part along the straight portion 12 and turning the lyre downwardly, all as shown in Fig. 3, the nuts being tightened after this has been accomplished in order to hold the rack in folded condition in the pocket.

30 It will be observed that my rack is of extreme simplicity both in construction and operation and may be made at a low cost. Furthermore, it is easily adjustable to suit the size of the user. It is further to be observed that the music is held at the proper distance from the eyes of the user and at the most convenient level, thereby avoiding eye strain or unusual mental effort in following the music while marching. 35 The rack being held naturally between the arm pit and the forearm when the latter is in the playing position, imposes no strain upon the user and preserves the music in a steady unwavering position, imposing no burden upon the eyes to follow it.

40 It is to be understood that my invention is not to be limited to the exact form of construction herein shown and described, since it is capable of embodiment in other forms, all within the scope of the following claims.

What I claim is:

1. A street music rack made in two parts relatively adjustable, one of said parts having a curved portion adapted to fit the front of the arm pit and shoulder of the user and the other of said parts being curved to engage the inner side of and

to ride over the top of the forearm when in playing position; said rack being held 60 in fixed position between the shoulder and the forearm by the normal pressure exerted upon it in a direction toward the shoulder by the forearm when in playing position. 65

2. A street music rack made in two parts relatively adjustable, one of said parts having a curved portion, adapted to fit the arm pit and the front of the shoulder, and a forwardly extending straight portion and the other of said parts being movably mounted upon the straight portion of said first part in approximately perpendicular relation thereto in position to engage the inner side of the forearm when in playing 70 position, said second part having its forward end bent over to engage the top of the forearm for carrying music holding means. 75

3. In a street music rack, the combination 80 of a part having a curved portion for fitting the front of the shoulder and a forwardly projecting straight portion, a second part slidably mounted on the said straight portion of said first part, the longitudinal 85 axis of said second part being substantially right angled, and means for holding said two parts in adjusted relation.

4. In a street music rack, the combination 90 of two parts made of tubular material and relatively adjustable, one of said parts having its rear portion curved for engaging and fitting the front of the shoulder and its forward portion straight and the other of said parts having its longitudinal axis 95 substantially right angled for engaging the inner side and top of the forearm, whereby the rack is held against movement by the normal pressure of the forearm toward the shoulder when in playing position. 100

5. In a street music rack, the combination 105 of a part having a curved portion, adapted to project into the arm pit and to fit the front of the shoulder, and a straight portion, a second part adjustably mounted on the straight portion of said first part, the longitudinal axis of said second part being substantially right-angled for engaging the inner side and top of the forearm, means 110 for holding said two parts in adjusted position and music-holding means adjustably mounted adjacent the forward end of said second part.

In witness whereof, I hereunto set my hand this 2nd day of December, 1922.

WILLIAM B. GRIFFITH.
